UNITED STATES PATENT OFFICE

123,480

DESIGN FOR A TENNIS SHOE

Don C. Hubbard, Auburn, Maine

Application August 19, 1940, Serial No. 94,498

Term of patent 14 years

To all whom it may concern:

Be it known that I, Don C. Hubbard, a citizen of the United States, residing at Auburn, county of Androscoggin, State of Maine, have invented a new, original, and ornamental Design for a Tennis Shoe, of which the following is a specification, reference being had to the accompanying drawing, forming part thereof.

Fig. 1 is a side perspective view of a tennis shoe showing my new design, both sides of which present substantially the same appearance, and

Fig. 2 is a side elevation of the shoe shown in Fig. 1.

I claim:

The ornamental design for a tennis shoe, as shown and described.

DON C. HUBBARD.
